UNITED STATES PATENT OFFICE.

THOMAS R. BROWN, OF SPARKILL, NEW YORK, ASSIGNOR TO THE WESTINGHOUSE AIR BRAKE COMPANY, OF WILMERDING, PENNSYLVANIA, A CORPORATION OF PENNSYLVANIA.

COMBINED CAR AND TRAIN-PIPE COUPLING.

1,243,701.

Specification of Letters Patent. Patented Oct. 23, 1917.

Application filed December 28, 1915. Serial No. 68,990.

To all whom it may concern:

Be it known that I, THOMAS R. BROWN, a citizen of the United States, and a resident of Sparkill, in the county of Rockland and 5 State of New York, have invented a certain new and useful Improvement in Combined Car and Train-Pipe Couplings, of which improvement the following is a specification.

This invention relates to combined car 10 and train pipe couplers, and more particularly to couplings of this character known as the rigid lock type, in which hook-shaped projections having diagonal vertical plane surfaces engage each other by a relative 15 lateral movement, and are tightly clamped together by pivoted locking levers or other automatic clamping means, and one of the objects is to provide improved fluid pressure means for actuating the locking levers 20 to release the couplers.

Another object is to provide improved valve devices, operated by the coming together of the couplers, or by their separation, or by the fluid admitted to release the 25 coupler locks, for controlling communication through the train pipe connections.

These and other objects will hereinafter more fully appear from the following description of one form of apparatus embodying my improvement, the novel features and 30 combinations being set forth in the appended claims.

In the accompanying drawings: Figure 1 is a horizontal section of one of the counterpart couplers, a portion thereof being 35 taken through the valve device controlling the train brake pipe connection; Fig. 2, a horizontal section through a portion showing another form of valve which may control a reservoir pipe connection; Fig. 3, a side view of the coupler with the pipe sections and operating cylinder detached; and Fig. 4, a horizontal section showing a modified form of device for actuating the coupler lock.

According to the construction shown in the drawings, the coupler comprises a main casting or coupler head, 12, adapted to be secured, preferably by a pivotal connection, 40 to the draw bar (not shown) and having a hook shaped projection, 14, provided with a vertical plane surface, 15, inclined at an angle to the line of draft and adapted to engage and interlock with a corresponding 45 surface on the projection of a counterpart

coupler by a relative lateral movement when said couplers come together in the act of coupling. Each coupler is also provided with a movable lock, 16, preferably pivoted as shown, and adapted to bear against a surface, 17, on the outer side of the projection, 14, of the counterpart coupler and hold said couplers securely clamped together when in coupled position. The locking lever, 16, is connected by the rod, 11, with the head, 9, 60 having roller, 7, operated by the cam, 6, mounted on vertical shaft, 8, which may be manually actuated by a handle, 5, either directly or through a gear connection, as shown. A spring, 10, bears against the 70 head, 9, and normally tends to extend the lever, 16, to its locking position.

For the purpose of releasing the lock by fluid pressure, I provide a cylinder, 20, containing a piston, 18, and having a mechanical connection for shifting the head, 9, to release the lock. As shown in Fig. 1, this connection comprises the loose push rod, 21, pivotally attached to the cam, 6, while in the modification shown in Fig. 4, the piston 75 rod, 21^a, bears against an extension, 9^a, of the head, 9. In this construction the lock may be manually released by turning the shaft, 8, and cam, 6, without moving the piston rod, and when fluid is admitted to 80 act on the piston, 18, the head, 9, will be pushed out independently of the movement of the cam, 6. In the construction shown in Fig. 1, the movement of the piston by fluid pressure operates to rotate the cam, 6, and 85 thereby release the lock. A spring, 19, may be employed to assist the return movement of the piston.

In order to establish a connection for the train pipe lines through the coupling, one 90 or more passages are formed for communicating with the train pipe lines, or preferably, the train pipe sections, 24, are bolted to the coupler, extending through the opening therein, and each provided with a gasket, 25, at 100 its end and adapted to engage a corresponding gasket of the counterpart coupler when the same are coupled together. There may be one or more train pipe passages connected through the coupler, two being contemplated 105 in the drawing, one for the train brake pipe and the other the reservoir pipe for connecting the several main reservoirs of the air brake system through the train.

The passages through the train pipe sec- 110

tions are provided with valves for controlling same. Such valves may be of the puppet type, as shown at 26, Fig. 2, having a stem, 27, extending through the casing, and a spring, 28, normally tending to close the valve. For opening the valve automatically upon the coming together of the two counterpart couplers, I provide a plunger, 30, slidably mounted in the coupler head and 10 extending in a direction parallel with the diagonal locking faces of the coupler, one end of the plunger projecting into the pocket of the coupler, and adapted to be engaged by a surface, 29, upon the forward end of the counterpart coupler during the last part 15 of the lateral locking movement as the couplers engage each other on said diagonal abutting surfaces. The other end of the plunger may be provided with a head, 31, for actuating the stems of one or more valves. By this means a valve, such as shown in Fig. 2, may be automatically opened and closed by the movement of the couplers.

For controlling the train brake pipe, however, I prefer to employ a valve device, such 25 as shown in Fig. 1, which will have the function of closing quickly when the fluid pressure is admitted to release the couplers, but will remain open temporarily in case the 30 couplers are accidentally pulled apart, in order to vent a sufficient amount of air from the brake pipe to cause an automatic application of the brakes. According to this construction, the valve, 32, is provided with a 35 piston head, 33, mounted in a cylindrical chamber, 34, the space, 35, around the valve communicating with the train brake pipe. For controlling the pressure in chamber, 34, at the back of piston, 33, there is provided a 40 small pilot valve, 36, mounted on a piston valve, 37, and having a stem, 38, extending through an opening in the piston valve, and into the chamber, 34, both valves having seats around the stem. A port, 41, leads to 45 the atmosphere, while port, 40, communicates with the cylinder of piston, 18, for supplying fluid under pressure to valve, 36, at the same time that it is admitted to said piston from a supply pipe, 42. A spring, 39, 50 normally holds the valves, 36 and 37, seated against the train pipe pressure in chamber, 34, when the couplers are separated and the valve, 32, closed. A stem, 43, extends from the head, 31, through the casing, and 55 through the valve, 32, into the chamber, 34, where it is provided with a head for sealing the opening through the valve, 32, and preventing leakage around said stem. A spring, 44, is located on the stem, 43, between a 60 shoulder and the valve, 32.

The operation of this valve device is as follows: When the coupler heads are brought together in the act of coupling, the forward end, 29, of one coupler engages the plunger, 65 30, of the other, pushing the same inward at

the same time that the couplers reach their locking position. This movement serves to push in the stem, 43, which immediately engages the end of the stem, 38, and unseats the valve, 37. During this movement, the valve piston, 37, remains seated against the valve, 36, by the air pressure acting on the inner face of said valve piston. The air pressure from the brake pipe and space, 35, which had previously equalized through the small groove 46, around piston, 33, into chamber, 34, is thus vented to the atmosphere through port, 41, and the train pipe pressure acting on the under side of valve, 32, and piston, 33, forces the same open and seats the piston against its gasket, 47, which is the normal open position of the valve when the parts are coupled together. The plunger head, 31, may be provided with gaskets, 45, located around the valve stems for the purpose of engaging the casing of the train pipe section or sections and preventing leakage therefrom around said stems when the parts are coupled together with the train pipe valves open.

When it is desired to release the couplers for uncoupling, fluid is admitted to pipe, 42, and cylinder, 20, for actuating the pistons, 18, to release the coupler lock, 16, and at the same time the fluid flows through the port, 40, where it acts upon the piston valve, 37, to force the same to its seat and close the exhaust port, 41. The fluid under pressure then flows through the opening around the stem, 38, into chamber, 34, where it acts upon the back of piston head, 33, and forces the train pipe valve, 32, to close. During this movement, the valve, 36, remains open, being so held by the stems, 30, 43 and 38, and the valve, 32, slides along the stem, 43, compressing the spring, 44. In this way, the train pipe valve is closed prior to the separation of the couplers, and when said couplers are pulled away from each other, the springs, 39 and 44, expand, returning the stems to normal unlocked position, and closing the valve, 36.

If, when coupled together, the couplers should be accidentally pulled apart, the valves, 32, will remain open a short period 115 of time until the train pipe pressure acting on said valve and piston, 33, has reduced sufficiently to be overcome by the spring, 39, whereupon the valve will be closed. This permits a sufficient reduction in train pipe 120 pressure to effect an automatic application of the brakes.

It will now be seen that I have provided an improved combined car and air brake coupler in which the train pipe valve is 125 closed by the fluid pressure mechanism prior to the release of the coupler locks, so that in uncoupling, the couplers will not be separated before the brake pipe is closed. Also that the safety feature of venting the 130

brake pipe to cause an automatic application of the brakes in case of an accidental separation of the couplers is preserved.

Having now described my invention, what I claim as new and desire to secure by Letters Patent is:

1. In a car coupling, the combination of a coupler head having a train pipe passage, and an opening adapted to register with a corresponding opening of a counterpart coupler, a valve for controlling said passage, a stem extending through the wall of said passage, and a slidable plunger mounted in the coupler head for actuating said stem and having a gasket surrounding said stem to seat against said wall.

2. In a car coupling, the combination of a coupler head having a projection provided with diagonal plane surfaces adapted to engage corresponding abutting surfaces on a counterpart coupler by a lateral movement in coupling, a train pipe passage having an opening adapted to register with the corresponding opening of a counterpart coupler, a valve for controlling said passage, and a plunger slidably mounted in a direction substantially parallel with said abutting surfaces for operating said valve.

3. In a car coupling, the combination of a coupler head having a train pipe passage, and an opening adapted to register with a corresponding opening of a counterpart coupler, a valve for controlling said passage, a pilot valve controlling the pressure acting on said train pipe valve, and a stem extending through the train pipe valve and operated by the coming together of the counterpart couplers for opening said pilot valve.

4. In a car coupling, the combination of a coupler head having a train pipe passage and an opening adapted to register with a corresponding opening of a counterpart coupler, a valve for controlling said passage, a piston connected to said valve, a stem extending through said main valve and

piston, a pilot valve having a stem arranged in line with said main stem and controlling the pressure on one side of said piston.

5. In a car coupling, the combination of a coupler head having a train pipe passage 50 and an opening adapted to register with a corresponding opening of a counterpart coupler, a valve for controlling said passage, a piston connected to said valve, a valve operated by the coming together of the 55 counterpart couplers for venting fluid from the rear of said piston, and a valve operated by fluid pressure for closing said vent and opening a supply port to said piston.

6. In a car coupling, the combination of 60 a coupler head having a train pipe passage and an opening adapted to register with a corresponding opening of a counterpart coupler, a valve for controlling said passage, a piston connected to said valve, a piston valve controlling the pressure in said piston chamber, and a vent valve mounted 65 on said piston valve and having a stem extending through the same.

7. In a car coupling, the combination of a 70 coupler head having a movable lock, a piston for releasing said lock, a train pipe passage, a valve for controlling said passage, a piston connected to said valve, and means for admitting fluid under pressure to actuate 75 both of said pistons.

8. In a car coupling, the combination of a coupler head having a movable lock, a piston for releasing said lock, a train pipe passage, a valve for controlling said passage, 80 a piston connected to said valve, a vent valve for releasing fluid from said valve piston, and a valve operated by fluid supplied to said lock releasing piston for closing the vent and opening a supply port to said valve piston. 85

In testimony whereof I have hereunto set my hand.

THOMAS R. BROWN.
